UNITED STATES PATENT OFFICE.

JOHN C. DUEBER, OF CANTON, OHIO.

DESIGN FOR A WATCHCASE.

SPECIFICATION forming part of Design No. 22,056, dated December 13, 1892.

Application filed September 5, 1892. Serial No. 445,137. Term of patent 14 years.

To all whom it may concern:

Be it known that I, JOHN C. DUEBER, a citizen of the United States, and a resident of Canton, county of Stark, State of Ohio, have 5 invented and produced a new and original Design for Watchcases, of which the following is a full, clear, and exact description, reference being had to the accompanying drawings, making part of this specification.

10 Figure 1 is a view in perspective of a watchcase, illustrating my design; and Fig. 2 is an edge view of the same.

On the side and about central thereto is shown a circular portion A, which may be 15 either plain or ornamented, from which radiate a series of oval ribs B, that extend to the smooth circular periphery a of the lid. The

rim C, to which the lids are hinged, extends at its central portion b beyond or outside of the line defining the diameter of the lid. 20

The leading feature of my design is the oval ribs B, extending to the smooth circular periphery a of the lid.

What I claim, and desire to secure by Letters Patent, is—

The design for watchcases herein shown and described.

In testimony whereof I have hereunto set my hand this 1st day of September, A. D. 1892.

JOHN C. DUEBER.
